(57) **CLAIM**

The ornamental design for a dispenser housing, as shown.

DESCRIPTION

FIG. 1 is a perspective view of a dispenser housing, showing my design;

FIG. 2 is a front elevation view of the dispenser housing;
FIG. 3 is a left side elevation view of the dispenser housing;
FIG. 4 is a back side elevation view of the dispenser housing;

FIG. 5 is a right side elevation view of the dispenser housing;

FIG. 6 is a top view of the dispenser housing; and,
FIG. 7 is a bottom view of the dispenser housing.

The broken line showing is for illustrative purposes only and
forms no part of the claimed design.
